CLATHRATE COMPOUND FORMATION

Charles J. Busso, Oakland, and Ernest L. Walters, San Francisco, Calif., assignors to Shell Development Company, San Francisco, Calif., a corporation of Delaware

Application June 25, 1948, Serial No. 35,106

9 Claims. (Cl. 260—96.5)

1

This invention relates to a process for the formation of clathrate compounds. More particularly, it is concerned with an improved process for the fractionation of mixtures of organic materials by the formation of clathrate compounds with certain fractions thereof.

The fractionation of petroleum hydrocarbons is usually carried out by closely controlled distillation. Further processing for the removal of specific fractions, such as aromatics, is sometimes employed for the purpose of obtaining special products. Other mixtures of organic compounds require the use of fractional techniques in order to obtain products having a particular utility.

It is known that gasoline distillates comprise a mixture of hydrocarbons having various typical configurations. Essentially, these include straight-chain, branched-chain, and cyclic hydrocarbons, both saturated and unsaturated. Further, it is known that the octane rating of a gasoline varies inversely with the concentration of the straight-chain hydrocarbons in such gasoline. It follows that the removal of straight-chain hydrocarbons from a gasoline will result in a product having an improved octane number.

Certain compounds have been found to have the property of forming compounds which may be termed as "clathrate compounds." By the latter term is meant the general type of compound in which the one component imprisons another without necessarily having any strong attractive interaction with it. Outstanding examples of clathrate-forming materials are those having the general configuration:

wherein X is oxygen, sulfur, selenium or tellurium. Salts of these compounds, such as acetates and hydrochlorides, also form clathrate compounds. The most generally recognized reaction of this type comprises the formation of clathrate compounds between urea and straight-chain hydrocarbons. It has been found that such formation may be conducted in the presence of other types of hydrocarbons without the latter being affected. These clathrate compounds are crystalline materials which readily separate from liquid media upon their formation; hence, this clathrate-compound formation may be utilized for the separation of straight-chain hydrocarbons from gasoline distillates for the purpose of obtaining a raffinate having an improved octane rating.

2

The portion of any mixture which does not react with the clathrate-forming agent is to be considered as a "raffinate" for the purpose of this discussion.

5 Gasoline distillates vary widely in their composition, depending primarily upon the crude source from which they are obtained. Mid-Continent gasoline stocks, for example, normally contain straight-chain hydrocarbons over the 10 whole boiling range of the distillate. In this case, it usually becomes essential to treat the entire distillate with urea in order to obtain maximum octane improvement. Other distillates, such as those obtained from San Joaquin Valley 15 crude, differ in that they normally contain a relatively insignificant amount of lower-boiling straight-chain hydrocarbons, even though they have a substantial proportion of higher-boiling straight-chain hydrocarbons.

20 Investigation of the phenomenon of clathrate formation has disclosed the fact that an equilibrium is reached in the reaction mixture with regard to the proportion of straight-chain hydrocarbons which may be extracted from a mixture 25 under a given set of conditions. For example, when operating at room temperature, it has been found that after treatment with urea a reaction mixture will always contain a certain proportion of unreacted straight-chain hydrocarbons even though an excess of urea has been present. Various influences, to be discussed hereinafter, affect 30 this equilibrium.

It is an object of this invention to improve the 35 process of clathrate-compound formation. It is another object of this invention to apply this improved process to the extraction of petroleum distillates. It is specific of this invention to improve the octane rating of gasolines having substantially no lower-boiling straight-chain hydrocarbons by the use of an improved process of 40 clathrate compound formation.

Now, in accordance with this invention, it has 45 been found that the efficiency of clathrate compound formation may be substantially improved by concentrating the reactive materials prior to contacting with the clathrate-forming agent. This invention is especially applicable to the treatment of hydrocarbon mixtures with urea, and especially to gasoline distillates containing substantially no lower-boiling straight-chain hydrocarbons by having an appreciable amount of higher-boiling straight-chain hydrocarbons. As 50 more particularly pointed out hereinafter, the straight-chain hydrocarbons may be paraffinic or olefinic, while the non-straight-chain may be

branched paraffins, branched olefins, aromatics, cycloparaffins, naphthenes, etc.

A specific embodiment, as illustrated by the example appearing hereinafter, comprises the fractionation of such a gasoline distillate, preferably by means of careful distillation, into two fractions, A and B. The fraction A contains all of the lower-boiling hydrocarbons present in the original distillate, preferably boiling below 300° F. and having less than 9 carbon atoms. These will be non-straight-chain hydrocarbons, for the most part, together with any minor proportion of straight-chain hydrocarbons boiling in this lower-boiling range. The fraction B contains hydrocarbons boiling above the range of those present in fraction A and will comprise a mixture of straight-chain hydrocarbons and non-straight-chain hydrocarbons, preferably boiling above 300° F. and having more than 8 carbon atoms. The application of the present invention, then, comprises treating only fraction B with a clathrate-forming agent, such as urea, whereby the straight-chain hydrocarbons crystallize out in the form of clathrate compounds with urea, leaving as a raffinate the higher-boiling non-straight-chain hydrocarbons. The raffinate then comprises a heavy gasoline having substantially improved octane number. This raffinate subsequently may be blended, if desired, with at least part of fraction A or with any other desired gasoline distillate in order to obtain a gasoline substantially free of straight-chain hydrocarbons and having an improved octane rating.

The application of the process described above results in several advantages. The product obtained by the treatment of only the higher-boiling fraction is at least as good as, and usually better than, that which results from the treatment of the whole mixture. If the final product obtained by the present invention is better than that resulting from the treatment of the whole mixture, this is due to the equilibrium phenomenon discussed hereinbefore. However, even when products of equal quality are obtained, the important advantages of the present process include reduction in operational losses and substantial reduction in apparatus requirements.

The process applies both to hydrocarbon mixtures having no straight-chain lower-boiling hydrocarbons and to mixtures having only a minor amount thereof. The claims and specifications are considered to relate to both of these situations.

The use of urea in clathrate compound formation makes possible the formation of a wide variety of products, dependent upon the conditions of the treatment which are employed. The process is preferably conducted at temperatures ranging from about 35 to about 125° F., although higher or lower temperatures may be found suitable in certain instances. Preferably, the clathrate formation is carried out within the range 45-90° F.

Contact is usually obtained by intimate mixing of urea with the hydrocarbon mixture. Preferably, this is conducted in a continuous manner since it has been found that continuously formed clathrate compounds possess crystal structures which favor their separation from the raffinate.

The clathrate-forming agent, such as urea, is preferably dissolved in a suitable solvent, although it may be used in special instances in crystalline form. Solvents which have been found to have particular advantages include

water and aqueous alcohol. In order to obtain maximum clathrate compound formation, the solution should be maintained at all times as nearly saturated as possible with respect to the treating temperatures. In order to maintain saturation, additional urea may be added during the process. Alternatively, a large excess of urea solution may be employed with respect to the quantity of straight-chain hydrocarbons to be extracted. When stocks contain from eight to twenty per cent straight-chain hydrocarbons and when the treating temperature is 5-25° C., the ratio of saturation aqueous urea solution to the hydrocarbon mixture is preferably between about 2:1 and 10:1.

Certain polar solvents for the hydrocarbon mixture have been found to promote the maximum rate of complex formation and appear to aid in obtaining optimum crystalline structure, as well as to favor maximum clathrate compound formation. Solvents of this nature include especially the alcohols having four or five carbon atoms and the ketones bearing alkyl groups having from one to five carbon atoms each. Species of these solvents include secondary butyl alcohol, tertiary butyl alcohol, secondary amyl alcohol, methyl ethyl ketone and methyl isobutyl ketone. In order to obtain the optimum effect of the use of such diluents, they should be used in a ratio with the hydrocarbon mixture of from 3:1 to 1:4.

The inclusion of certain surface-active agents in the reaction mixture has been found to favor separation of clathrate compounds from the raffinate. Unless special precautions are taken, the surface of the clathrate crystals occludes substantial amounts of the raffinate materials. It is especially desirable, therefore, to employ a system wherein the clathrate crystals separate cleanly from the raffinate and associate entirely with the urea solution. Furthermore, due to the apparent adherence of the raffinate to the clathrate surfaces, the normal mixture is largely thixotropic in character. This results in viscosity difficulties during the separation of the clathrate compounds from the raffinate. The inclusion of certain types of surface-active agents in the reaction mixture has been found to favorably modify the thixotropic character thereof and to aid in causing the raffinate to separate from the clathrate crystals, the latter tending to associate with the aqueous phase.

Suitable types of surface-active agents include the alkali metal salts of organic sulfonic acids and of sulfonated dicarboxylic acids. These are especially effective if they are the sodium salts of alkyl aryl sulfonic acids or sodium salts of alkylated sulfosuccinic acid. Typical species include sodium dodecyl methylphenylsulfonate and the sodium salt of diethylsulfosuccinic acid.

Other suitable types of surface-active agents are high molecular weight secondary alcohols, such as 7-ethyl-2-methyl-undecanol-4.

The surface-active agents may be employed in amounts varying from about 0.1 to about 5.0 per cent, based on the weight of the hydrocarbon mixture. Their use causes the reaction system to have a reduced viscosity and to settle more rapidly into an upper and lower layer, the upper layer comprising the raffinate hydrocarbons and the lower layer comprising the remaining aqueous urea solution and the clathrate compounds.

The present process also may be applied to mixtures of hydrocarbons other than those containing the special type of gasoline distillate described hereinbefore. These may be hydrocarbon

mixtures obtained by the polymerization of natural gas or synthetic mixtures containing hydrocarbons having from four to sixteen carbon atoms. Straight-chain hydrocarbons forming clathrate compounds with urea include especially those having at least seven carbon atoms, such as octane, decane and dodecane. The principle upon which this invention is based applies as well to the fractionation of mixtures of polar compounds, such as alcohols, aldehydes, ketones, acids and esters.

The process is particularly described in the accompanying diagram, wherein a gasoline distillate having a boiling range of 90-410° F. was employed. Ten parts by volume of saturated aqueous urea solution were contacted with a mixture of two parts of the gasoline and one part of methyl ethyl ketone at a treating temperature within the range of 40-70° F. The gasoline stock was one obtained from a San Joaquin Valley petroleum crude and contained substantially no straight-chain hydrocarbons boiling below about 325° F.

The stock 1 was fractionated into two fractions by distillation. The fraction 2 boiled from 90° to 325° F. and contained only non-straight-chain hydrocarbons in this boiling range. The higher boiling fraction 3 had a boiling range of 325-410° F. and contained both straight-chain hydrocarbons and non-straight-chain hydrocarbons in this boiling range. The fraction 3 was treated with urea solution 4 as described above. The crystalline clathrate compounds 5 which formed between urea and the straight-chain hydrocarbons present in fraction 3 were separated from the unaffected raffinate by filtration. The raffinate 6, comprising non-straight-chain hydrocarbons having a boiling range of 325-410° F., was combined with fraction 2 to give a blend 7 having substantially improved octane rating.

The original gasoline distillation had an octane number of 49. The blend 7, obtained as described above, had an octane rating of 56. For comparison, the original gasoline distillate having a boiling range of 90-410° F. was treated with urea solution without being subjected initially to fractional distillation. The raffinate from this reaction also had an octane rating of 56.

The fractions 2 and 3, described above, were substantially equal in size; hence, the full improvement in octane possible has been obtained by the process of the present invention, although only fifty per cent of the original distillate was treated. The economical and technical advantages of such a process are immediately evident.

We claim as our invention:

1. In a process for the fractionation of hydrocarbon mixtures comprising straight-chain hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the presence of from about 0.1% to about 5% by weight based on the hydrocarbon mixture of a surface-active agent of the group consisting of sodium salts of alkyl aryl sulfonic acids, sodium salts of alkylated sulfo-succinic acid and high molecular weight secondary alcohols.

2. In a process for the fractionation of hydrocarbon mixtures comprising straight-chain

hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the presence of from about 0.1% to about 5% by weight based on the hydrocarbon mixture of a sodium salt of alkyl aryl sulfonic acids.

3. In a process for the fractionation of hydrocarbon mixtures comprising straight-chain hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the presence of from about 0.1% to about 5% by weight based on the hydrocarbon mixture of a sodium salt of alkylated sulfo-succinic acid.

4. In a process for the fractionation of hydrocarbon mixtures comprising straight-chain hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the presence of from about 0.1% to about 5% by weight based on the hydrocarbon mixture of a high molecular weight secondary alcohol.

5. A process according to claim 1 wherein the hydrocarbon mixture is a gasoline distillate.

6. In a process for the fractionation of hydrocarbon mixtures comprising straight-chain hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the presence of from about 0.1% to about 5% by weight based on the hydrocarbon mixture of 7-ethyl-2-methyl undecanol-4.

7. In a process for the fractionation of hydrocarbon mixtures comprising straight-chain hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the presence of from about 0.1% to about 5% by weight based on the hydrocarbon mixture of the sodium salt of diethyl sulfo-succinic acid.

8. In a process for the fractionation of hydrocarbon mixtures comprising straight-chain hydrocarbons and non-straight-chain hydrocarbons wherein said mixtures are contacted with an aqueous urea solution whereby crystalline molecular complexes are formed between urea and straight-chain hydrocarbons and subsequently are separated from the non-crystalline components, the improvement which comprises conducting said contacting and separation in the pres-

ence of from about 0.1% to about 5% by weight based on the hydrocarbon mixture of sodium dodecyl methylphenylsulfonate.

9. In the process for the formation, precipitation and separation of crystalline molecular complexes by contacting a higher straight chain alkane having at least seven carbon atoms with urea in aqueous solution, the improvement which consists in adding solely a small amount of a surface-active agent of the group consisting of sodium salts of alkylaryl sulfonic acids, sodium salts of alkylated sulfosuccinic acid and high molecular weight secondary alcohols to said aqueous solution.
